Timothy Beach of Clinton County, Ohio
Letter Patent

The Schedule of rights in the Letter Patent and making part of the same containing a description in the words of said Timothy Beach himself of his improvement in the art of Propelling Boats.

To all to whom these presents shall come. To wit it is known that Timothy Beach of the County of Clinton and State of Ohio, have invented a new and useful improvement in propelling Boats. & that the following is a full and exact description of the construction and operation of said machine as invented or improved by one, viz. of the subjoined sketch. A is a furnace. B is the Boiler. C Safety valves. D trial cock. E is the pipe conducting the steam from the boiler to the Steam chest F. G the suspended or cylinders or tubes extending from the steam chest to the horizontal or oblique tubes H H. I I two valves opening ^{water} on the under side of the oblique tubes. J J valves on the ends of the tubes H H. The dotted lines are intend to represent a Boat immersed in water to the horizontal line K in consequence of the Boat being immersed in water. The valves I I opening inward, admit the water into the tubes H H and from thence into the perpendicular tubes or cylinders G G. The steam passes thro' the pipe E into the steam chest F & by an alternate motion of closing valves the steam is permitted to act on the surface of the water in the cylinders G G. which causes the water to discharge with the velocity of the waves J J. which acting against the surrounding water, impels the Boat forward. What I claim as my invention or improvement is the application & construction generally of the above described machine.
